UNITED STATES PATENT OFFICE.

JOHN O. MORRIS, OF DAVENPORT, IOWA.

ASH-SCREEN.

1,150,615.

Specification of Letters Patent.

Patented Aug. 17, 1915.

Application filed January 14, 1914. Serial No. 812,093.

To all whom it may concern:

Be it known that I, JOHN O. MORRIS, a citizen of the United States, residing at Davenport, in the county of Scott, State of Iowa, have invented certain new and useful Improvements in Ash-Screens; and I do hereby declare the following to be a full, clear, and exact description of the invention, such as will enable others skilled in the art 10 to which it appertains to make and use the same.

This invention relates to ash screens.

The object of the invention resides in the provision of an ash screen which can be 15 readily inserted through the ash door of a furnace in position to directly receive the ashes as the grate is shaken, or dumped said screen embodying a structure permitting easy reciprocation thereof while disposed in the furnace to effect screening of the ashes.

A further object of the invention resides in the provision of an ash screen which when inserted in the furnace and operated to 25 screen the ashes will prevent dust from escaping from the interior of the furnace to the exterior thereof.

A still further object of the invention resides in the provision of an ash screen which 30 can be removed from the interior of a furnace without disturbing that portion of the ashes which have passed through the screen to a position upon the bottom of the furnace.

Another object of the invention resides in 35 the provision of an ash screen of the character referred to which will be simple in construction, efficient in use and which may be manufactured at a comparatively small

40 cost.

With the above and other objects in view the invention consists in the details of construction and in the arrangement and combination of parts to be hereinafter more 45 fully described and particularly pointed out in the appended claim.

In describing the invention in detail reference will be had to the accompanying drawings wherein like characters of reference 50 denote corresponding parts in the several views, and in which—

Figure 1 is a vertical section of a portion of a furnace showing the improved screen in position to receive ashes upon shaking or 55 dumping the grate; Fig. 2, a plan view of the screen; Fig. 3, a section on the line 3—3

of Fig. 2; and Fig. 4, a section on the line 4—4 of Fig. 2.

Referring to the drawings the improved screen is shown as comprising a frame A 60 which embodies front and rear members 10 and 11 and side members 13 and 14 which latter constitute the supporting runners of the screen. The runners 13 and 14 are connected at their forward ends by the member 10 and at their rear ends by the member 11. A cleat 15 is secured against the member 11 of the frame A as clearly shown in the drawing. To this frame A and cleat 15 is secured a screen 16 in any suitable manner. 70 On the upper edges of the members 10, 13 and 14 are secured members 17, 18, and 19 respectively which form with the upper part of the member 11 a tray to receive the ashes and other materials shaken or dumped from 75 the grates and also further securing the screen 16 by clamping same between the members 17, 18 and 19 and the frame A.

The upper edge of the side members 18 and 19 are beveled as at 20 for a purpose 80 that will now appear. Hingedly secured to the side members 18 and 19 are wings or leaves 21 and 22 respectively, which when actively disposed are adapted to rest upon the upper beveled edge 20 of respective 85 members 18 and 19, whereby said wings are supported in an outward inclination. These wings 21 and 22 are designed to be utilized only when the width of the grate of the furnace is in excess of the width of the 90 ash pit door and the screen 16, the wings under such condition serving to catch ashes descending beyond the limits of the screen and directing same upon the latter.

The rear member 11 of frame A is provided with a handle 23 for convenience in inserting the screen through the ash-pit door of a furnace and also for convenience in effecting reciprocation of the device in the operation of treating the ashes. 95

It will be noted that during the screening operation that the passage of the dust to the exterior of the furnace is prevented by the passing of air into the fire-box due to the draft of the furnace and chimney. It will 105 be further noted that as the member 10 is relatively narrow, the whole screen may be withdrawn from the interior of the furnace without disturbing the material which has passed through the screen. 110

What is claimed is:—

A device of the class described comprising

a frame including supporting runners having their ends connected by cross bars, on the upper edge of which is secured a screen, a tray secured to upper edge of the supporting runners and cross bar over the screen, the upper edges of the side members of the tray being inclined inwardly, wings hinged to said side members and supported by the upper edges of the side members in an in-

clined position to receive the material fall- 10
ing outside of the limits of the screen.

In testimony whereof, I affix my signature, in the presence of two witnesses.

JOHN O. MORRIS.
